UNITED STATES PATENT OFFICE.

FRED J. HEIDEMAN, OF DETROIT, MICHIGAN.

REFRIGERATING APPARATUS.

Application filed September 21, 1925. Serial No. 57,790.

This invention relates to refrigerating apparatus and more particularly to the refrigerator or brine tank thereof.

One of the important objects of the invention is to provide an improved arrangement or construction of expansion coil for use in connection with the brine tank and designed to facilitate the assembling of the coil and tank. Additional advantages of the construction reside in the facility with which visual inspection and tests may be conducted and the facility with which the coil may be repaired.

Another important object of the invention is to induce a highly efficient thermo-siphon circulation and this object is accomplished by the configuration and construction of the coil and its relation to the brine tank.

The invention has also among its objects, to simplify, render more efficient, and improve generally devices of this character, and the above as well as other objects, advantages, and novel details of construction, will be made more apparent as this description proceeds, especially when considered in connection with the accompanying drawings wherein.

Fig. 1 is a top plan view of the brine tank constructed in accordance with this invention.

Fig. 2 is an end elevation thereof, and Fig. 3 is a fragmentary perspective view of the expansion coil removed from the brine tank.

Referring now particularly to the drawings wherein like reference characters indicate like parts, it will be noted that there is provided a brine tank 10, which in mechanical refrigerating apparatus is designed to contain brine or some other liquid having a relatively low freezing point. This tank may be of any suitable construction and is provided with openings or passages therethrough indicated herein by the reference characters 11 and 12. These passages are open at the ends of the tank and not only increase the radiating surface of the tank but provide compartments for freezing water cubes, fruit and the like in the manner customary with mechanical refrigeration. The walls of these openings also divide the tank and define a path of circulation followed by the brine or other similar fluid when the thermo-siphon circulation is induced by the expansion coil yet to be described.

The top 13 of the tank is preferably formed separately therefrom and adapted to be secured thereto in any suitable manner, but this removable top affords means for inserting the expansion coil. Secured to the top 13 are fittings 14 and 15 for connection with the intake and outlet respectively of the expansion coil.

The expansion coil indicated generally by the reference character 16 is substantially an inverted L-shape in cross-section and is constructed of a single length of preferably copper tubing bent to the configuration or shape substantially as shown in Figure 3. This construction includes a plurality of superposed successively arranged coils, the coils being formed by providing a plurality of returnbent curves 17 at the upper end of the coils and a plurality of returnbent curves 18 at the bottom thereof, these returnbent curves 17 and 18 being successively arranged and in substantial alignment, the parts of the tube forming the intermediate connecting portions of the coil being preferably crossed substantially as illustrated. While the particular manner in which the tube has been bent to form the coil 16 has been found efficient and advantageous by reason of the greater capacity obtained, still it will be immediately obvious that various other coil configurations may be employed without sacrificing the advantages of the invention if the general inverted L-shape is retained.

In Fig. 1 the reference character 19 indicates the customary expansion valve connected by means of a nipple 20 to the conduit 21 which is connected to the compressor. The expansion valve 19 is connected, as for instance by means of the coupling flange 22 to the fitting 14 to which the intake end 23 of the expansion coil is connected. A sensitizer or thermo-responsive device 24 is suitably connected to fitting 15 to which the outlet end 25 of coil 16 is connected. The sensitizer 24 is connected by means of a nipple 26 to a tube 27 by means of which the refrigerating medium flowing out of coil 16 is conducted to the intake port of the compressor. By means of the nipple 28 connection is made with a tube 29 which extends to a pressure responsive device such, for instance as a thermostat, usually employed in mechanical refrigerating apparatus for controlling the compressor motor switch. The tank 10 may be filled with

brine or other fluid having a relatively low freezing point by means of a filling opening closed by filler cap 30.

In operation, with the refrigerating medium in the coil 16 a thermo-siphon circulation will be induced by reason of the cooling of the brine or other fluid at the top and lefthand side of the tank as viewed in Fig. 2. This cooled fluid will fall and 5 place the warmer fluid contained in the bottom and righthand side of the tank in a direction substantially as indicated by the arrows. As the warmer fluid rises to the 10 top of the tank it comes in contact with the 15 expansion coils contained therein. It will become cooled and drop down the lefthand side of the tank in proximity to the coils therein contained, thus inducing a continuous circulation which eventually will cause 20 a complete cooling of all of the fluid within the tank.

As mentioned hereinbefore, the arrangement of the coil within the tank induces a maximum thermo-siphon circulation by 25 which a maximum refrigerating efficiency is obtained. Furthermore by reason of the fact that the coil is of an inverted L-shape in cross-section it may be positioned within the tank from the top without interference 30 with the openings 11 and 12 formed in the tank. In assembling this is particularly advantageous because the tube may be given a pressure immersion and visual inspection prior to the inspection of the tank proper. 35 This arrangement, in addition to facilitating to a great degree the assembling of the parts, renders the coil more readily accessible for removal and repair.

While a specific embodiment of the invention has been described and illustrated herein somewhat in detail, it will be immediately apparent that various changes and modifications in the specific structure illustrated may be resorted to without departing from 40 the spirit and scope of this invention, and to this end reservation is made to make such changes as may come within the purview of the accompanying claims.

What I claim as my invention is:

50 1. In a refrigerating apparatus, a brine tank formed with a separate top wall, a walled opening formed in said tank and extending therethrough from side to side, and

an expansion coil comprising a series of substantially L-shape loops insertable in said tank through the top thereof to clear said walled opening, with a portion thereof disposed adjacent one vertical wall of the tank and another portion disposed adjacent the top of the tank. 55 60

2. In a refrigerating apparatus, an expansion coil formed by a pipe bent to form a series of substantially similar loops offset from each other in the plane of said loops, said loops being bent as a unit about 65 an axis transverse to said loops, giving the unit substantially an L-shape. 70

3. In a refrigerating apparatus, the combination with a tank for receiving a liquid to be cooled, of a cooling coil forming a 75 series of loops arranged substantially in the same plane and bent transversely of said loops to form relatively transverse portions, one extending downwardly adjacent one wall of said tank and the other extending 80 substantially horizontally adjacent to the top of the tank. 75

4. In a refrigerating apparatus, a brine tank provided with a walled opening extending therethrough from side to side, and 85 an expansion coil comprising a plurality of successively arranged overlapping loops bent at substantially right angles intermediate the ends thereof arranged within said tank with one portion adjacent the top of the 85 tank and the other portion adjacent one vertical wall of the tank, said coil insertable from the top of the tank to clear said walled openings. 90

5. In a refrigerating apparatus, a tank 90 for receiving a liquid to be cooled provided with a walled opening extending therethrough from side to side in a direction substantially parallel to a third side, a substantially L-shaped expansion coil comprising a series of successively overlapping substantially L-shaped loops arranged within said tank with one of the transverse portions thereof adjacent the top of said tank, and the other transverse portion extending 95 downwardly between said walled opening and a side of the tank parallel to the walls of said opening. 100

In testimony whereof I affix my signature.

FRED J. HEIDEMAN.
